UNITED STATES PATENT OFFICE.

ERNEST B. CROCKER, OF STRATFORD, CONNECTICUT, ASSIGNEE TO MANNING, MAXWELL & MOORE, INC., OF NEW YORK, N. Y., A CORPORATION OF NEW JERSEY.

GAUGE.

Application filed April 17, 1920. Serial No. 374,540.

To all whom it may concern:

Be it known that I, ERNEST B. CROCKER, a citizen of the United States, residing at Stratford, county of Fairfield, State of Connecticut, have made a certain new and useful Invention in Gauges, of which the following is a specification.

This invention relates to gauges, and particularly to gauges of the Bourdon tube 10 type.

The object of the invention is to simplify the structure of devices of this nature, to reduce the cost of manufacturing the same, and to render the same more efficient in use.

15 A further object is to provide means which are simple and efficient for compensating for the vagaries of the Bourdon tube and its associated parts developed in the manufacture and assembly thereof.

20 A further object is to provide a gauge structure in which the usual dial hand spindle actuating gear segment and slide member, the hair spring, and the link connecting the slide member with the free end of the Bourdon tube, as well as the supporting frame in which the parts are mounted, are dispensed with, thereby greatly reducing the cost of manufacture of the gauge.

25 A further object is to provide means which are simple and efficient for adjustably regulating the fulcrum point about which the Bourdon tube operates, in calibrating and adjusting the device after assembly of the parts thereof.

30 Other objects of the invention will appear more fully hereinafter.

Referring to the accompanying drawing, and to the various views appearing thereon,

35 Fig. 1 is a view face plan, parts broken out and in section, of a gauge structure embodying the principles of my invention, the dial plate and hand or pointer being omitted.

40 Fig. 2 is a view in central longitudinal section of the same, on the line 2, 2, Fig. 1, looking in the direction of the arrows.

45 Fig. 3 is a detached detail view in section on the line 3, 3, Fig. 2, looking in the direction of the arrows.

50 Fig. 4 is a view in elevation of the parts shown in Fig. 3.

Fig. 5 is an enlarged broken detached de-

tail view showing a means for connecting to the end of the Bourdon tube the flexible connection for actuating the dial hand 55 spindle.

Fig. 6 is a view similar to Fig. 1 showing a modified arrangement embodying and included within the spirit and scope of my invention.

Fig. 7 is a detached detail view in elevation of the adjustable fulcrum device shown in Fig. 6.

The same part is designated by the same reference numeral wherever it occurs 65 throughout the several views.

In the drawings, reference numeral 10, designates a casing in which is suitably mounted a socket piece 11, for connection with the source of pressure to be indicated by the gauge. This socket piece may be of any desired structure and mounted in any suitable manner in the casing. A simple 70 illustrative arrangement is shown wherein the socket extends through an opening in the bottom wall of the case, and is flanged, as at 12, the flange seating and being clamped against the inner surface of the case bottom by means of a nut 13, applied to exterior threads on the shank of the socket. The flanged socket is held against turning 75 by means of a post 14, which extends through a hole in the flange 12 thereof and through a hole in the bottom wall of the case. To the post 14 the end of the Bourdon 80 tube 16 is attached in any suitable or convenient manner, as for instance, by sleeving thereover. If desired, and as shown in Fig. 2, the end portion 15 of the tube 16 may itself constitute such post and is anchored 85 in the socket extending through and being tightly fitted into the opening in the flange 12 of the socket piece and extending through an aligned opening in the end wall of the case 10. This end portion of the tube is 90 anchored in place by soldering the same therein. The upper surface of the socket piece is formed with a raised rib 18, the function of which is to form a bridge between the anchorage for the Bourdon tube 95 and the bearing of the dial hand arbor, thereby preventing the solder employed in securing the tube in place on the socket from gaining access to and clogging the

dial hand arbor, and also to form a convenient indication for properly locating the parts in assembling and securing them.

Mounted in a hole in the socket piece, and secured therein is a vertically extending post 19. Rotatably mounted on this post is a sleeve 20 formed with a pintle 21 at one end thereof, said pintle extending through the dial plate 22, and carrying the hand or pointer 23.

In accordance with the principles of my invention this sleeve 20, carrying the hand or pointer 23, is rotatably actuated by the movements of the Bourdon tube under the influence of pressure variations. The connections intermediate the free end of the tube and the sleeve rotatively actuating the latter may be of a wide variety of forms. In Figs. 1, 3, 4 and 5, I have shown one simple and efficient arrangement which I have found to possess many practical advantages. According to this arrangement a flexible connection 24, is connected at its ends to the free end of the tube and intermediate its ends is coiled about the sleeve. A simple arrangement is shown wherein a collar 25 is applied to the sleeve, and said collar is formed with a lip or tongue 26, cut therein, which, when deflected affords an opening through the collar. One run or leg of the flexible connection 24, is passed around the sleeve 20 above the collar 25, and then is passed through the opening formed by deflecting the lip or tongue 26, and is then wound around the sleeve below the collar. I have found that a single turn of the connection 24 around the sleeve 20 above the collar 25, and a single turn around the sleeve below the collar is sufficient, though it is to be understood that my invention is not to be limited in this respect. If desired, the connection 24 may be locked upon the sleeve 20, by simply pinching the lip or tongue 26, thereagainst, after said connection is coiled upon the sleeve. It will thus be seen that the connection is secured to the sleeve at its midpoint, from which point it leads in opposite directions around and from the sleeve. The connections of the ends of the flexible connection to the free end of the Bourdon tube may be effected in any suitable or convenient manner. A simple and efficient arrangement is shown, to which, however, I do not desire to be limited or restricted, wherein a tip member 27 is fitted to the free end of the tube, and is formed with lips or tongues 28, between which one end of the flexible connection 24 is received and held in place by crimping or pinching said lips or tongues thereon. The other end of the flexible connection is secured upon a hook 29 also formed on the tip member 27. One of the legs or runs of the connection 24 intermediate the sleeve 20 and the free end of the

Bourdon tube contains an extensible portion 30, which may be conveniently a coiled spring. In the operation of the device, when the free end of the Bourdon tube moves in a direction away from the sleeve 70 it exerts a pull on one leg or run of the flexible connection, the yielding or extensible portion 30, in the other leg or run of the connection permitting such pull to be exerted upon the sleeve to rotatively move 75 the latter in one direction. The movement is against the yielding tension of the extensible portion 30, which will restore the sleeve to its initial position when the pull of the tube relaxes under the influence of a reduction of pressure therein.

It may sometimes be desirable to arrest and prevent the further rotative movement of the sleeve 20 when a given degree of rotative movement has been imparted thereto, 85 in order to avoid the danger of twisting or breaking the hand or pointer after it has reached a limit of its throw. Again, in case an abnormal pressure is suddenly admitted to the tube 16, the danger is incurred of 90 causing damage or injury to the tube, or to unduly strain the tube and cause the same to become more or less set under the influence of the abnormal strain or pressure thereby imposed thereon. To avoid these 95 and other objections, I provide a short section 31 of slack in the flexible connection 24 around the extensible section 30 Fig. 3. This slack permits the proper functioning 100 of the extensible portion, as above described, when the device is operating under normal conditions, but in case of abnormal movement of the tube 16, the slack portion 31 will be taken up thereby arresting the action of the extensible portion 30, and locking the 105 sleeve 20 against further rotative movement because equal pulls will thereafter be imposed on the two legs or runs of the flexible connection 24.

As above indicated, my invention, in its 110 broadest scope, is not to be limited or restricted in respect to the connections for rotatively actuating the dial hand spindle or sleeve 20. For example, excellent results 115 may be obtained by providing the sleeve with a laterally extending arm 32, see Fig. 6, the outer end of which is pivotally connected by means of a link to the free end of the Bourdon tube.

Experience has shown that Bourdon tubes 120 frequently develop freakish peculiarities and characteristics which often differ in tubes even when made in the same way from the same material and of the same dimensions. These characteristics are sometimes referred to as the vagaries of the tubes, and they give rise to the necessity of accurately 125 adjusting each instrument after the parts thereof have been assembled and before they are sold or put into use, in order that the 129

instrument may give correct indications of pressure variations. It is among the special and important features and purposes of my present invention to provide means which are exceedingly simple, efficient and easily accessible for effecting the desired adjustment of the instrument to compensate for the vagaries of the tube after the tube and other parts have been assembled. In carrying out this part of my invention, and as a result of experimentation, I have found that by providing a suitable fulcrum for the tube about which the tube may rock in its distending movements under the influence of the pressure applied thereto, and by suitably adjusting such fulcrum in the direction of the length of the tube, I am enabled to adjust the free length or leverage of the free end of the tube and consequently the range of movement of the free end of the tube, thus affording a simple and convenient means for adjusting the instrument to compensate for any irregularities due to such vagaries or to the assembling of the parts. These objects and purposes may be attained in a wide variety of arrangements of an adjustable tube fulcrum point.

In Fig. 1 I have shown one illustrative arrangement which I have found to be simple and economical to manufacture and easy to apply, and wherein I employ an abutment, which, in this illustrative instance is shown as a roller, indicated at 34, which is interposed between the inner wall of the casing 10, and the tube 16, to form a fulcrum point for the free end of the tube. This fulcrum abutment is carried at the end of a shank member 35, in the form of a spring strip rod or wire of any suitable shape in cross section, which, in one form, is bent around an annular groove formed in the abutment 34. This shank member is bent to conform to the circumferential curvature of the case 10, and is disposed within and along the inner wall surface of the case outside the tube 16, as clearly shown. By shifting this shank member in the direction of its length the abutment 34 is correspondingly shifted in the direction of the length of the tube, thereby varying the fulcrum point about which the free end of the tube moves, that is, in effect, varying the effective length of the tube.

In order to facilitate the adjustment of the shank member 35, and to afford convenient and easy access thereto for adjustment from outside the case, I find it convenient to punch inwardly a portion 36 of the wall of the case, to form a loop, and to pass the shank or fulcrum carrying member 35 through this loop, whereby, by grasping the portion of said shank portion which is exposed to the outside of the case through the slot or opening 37, with a suitable tool the desired adjustment of said member and

of the fulcrum abutment 34 is effected. The abutment and its carrying member are held in the adjustments by friction between the tube and casing wall, and between the carrying member and loop 36 of the casing wall. 70

In Figs. 6 and 7 I have shown another illustrative arrangement of adjustable fulcrum wherein the bent end 38 of a spring strap or plate 39 constitutes the fulcrum bearing or abutment for the tube. This plate 39 is shaped to conform to the curvature of the inner wall surface of the case, and is applied and secured to said inner wall for circumferential adjustment. This adjustment is secured by providing a longitudinal slot 40 in said plate through which extends a clamping and guiding stud 41, mounted in the wall of the casing. By suitably loosening up the stud 41 the plate 39 may be adjusted in the direction of its length and secured in its adjusted position by again tightening up the said stud. 80

From the foregoing description it will be seen that I provide an exceedingly simple structure of gauge, which requires but few parts, is economical to manufacture, and is capable of being easily and quickly assembled. It will also be seen that I avoid the customary frame ordinarily employed in devices of this nature and the gear segment 95 and its adjusting slide member which require such a frame for their mounting, as well as the gear pinion on the dial hand spindle, and the ordinary form of hair spring, and that by eliminating these parts 100 I am enabled to very greatly reduce the cost of manufacture of the instrument, and this I am enabled to do in a structure which does not sacrifice anything of ruggedness and sturdiness, nor accuracy of indications. 105

It will also be seen that I provide means for quickly and accurately adjusting the gauge to compensate for inaccuracies or inequalities due to the vagaries of the tube, or to the manufacture or assembly of the parts. 110

Many variations and changes in the details of construction and arrangement of parts will readily occur to persons skilled in the art and still fall within the spirit and scope of my invention. I do not desire, therefore, to be limited in the broad scope of my invention to the details shown and described. 115

But having now set forth the objects and nature of my invention and various constructions embodying the principles thereof, what I claim as new and useful, and of my own invention, and desire to secure by Letters Patent is,—

1. In a Bourdon tube gauge, a casing, a Bourdon tube, a socket piece to which one end of said tube is anchored, said socket piece having a passage communicating with a source of pressure and with the tube and extending through an opening in the end 125 130

wall of the casing, and an anchor member connected to the tube and extending through a portion of the socket piece and the end wall of the casing to lock said socket piece against rotative movement.

2. In a Bourdon tube gauge, a casing, a Bourdon tube, a socket piece to which one end of said tube is anchored, said socket piece having a passage communicating with 10 a source of pressure and with the tube and extending through an opening in the end wall of the casing, said socket piece having a flange fitting against the inner surface of the end wall of the casing, an anchor member connected to the tube and extending 15 through openings in the socket flange and casing, and means for clamping said flange against the inner surface of the end wall of the casing.
3. In a Bourdon tube gauge, a casing, a Bourdon tube, a socket piece separate from the tube but to which one end of said tube is anchored, said socket piece having a passage communicating with a source of pressure and with the tube and extending 20 through an opening in the end wall of the casing, said socket piece having a flange fitting against the inner surface of the end wall of the casing, an anchor member connected to the tube and extending through 25 openings in the socket flange and casing, and a nut threaded on the shank of said socket piece to clamp the same to the casing.

4. In a Bourdon tube gauge, a casing, a Bourdon tube, a socket piece to which one end of said tube is anchored, said socket piece having a passage communicating with a source of pressure and with the tube and extending through an opening in the end 25 wall of the casing, and means for clamping said socket piece to the casing, said socket piece having a rib upon its inner end surface, said rib forming a bridge to separate the anchorage of the tube from an arbor bearing.

5. In a Bourdon tube gauge, a casing, a Bourdon tube, a socket piece to which one end of said tube is anchored, said socket piece having a passage communicating with 50 a source of pressure and with the tube and extending through an opening in the end wall of the casing, means for clamping said socket piece to the casing, a post secured in said socket piece, a sleeve rotatably mounted on said post, flexible connections intermediate the free end of the tube and said sleeve to rotatively actuate the latter, and a dial hand or pointer carried by said sleeve.

6. In a Bourdon tube gauge, a casing, a Bourdon tube, a socket piece to which one end of said tube is anchored, said socket piece having a passage communicating with a source of pressure and with the tube and extending through an opening in the end 60 wall of the casing, means for clamping said

socket piece to the casing, a post secured in said socket piece, a sleeve rotatably mounted on said post, connections intermediate said sleeve and the free end of said tube for rotatively actuating the latter, and a dial hand or pointer carried by said sleeve.

7. In a Bourdon tube gauge, a casing, a Bourdon tube, a socket piece mounted in said casing and to which one end of said tube is anchored a post fixed to said socket 75 piece, a member rotatively mounted on said post and carrying a dial hand or pointer, and flexible connections intermediate the free end of said tube and said rotative member.

8. In a Bourdon tube gauge, a casing, a Bourdon tube, a socket piece mounted in said casing and to which one end of said tube is anchored, a member rotatively mounted on said socket piece and carrying a 85 dial hand or pointer, and flexible connections intermediate the free end of said tube and said rotative member, said flexible connections including an extensible portion located between the free end of the tube and 90 the rotative member.

9. In a Bourdon tube gauge, a casing, a Bourdon tube and a spindle, a member rotatively mounted on said spindle carrying a dial hand or pointer, means to support one 95 end of the Bourdon tube, a flexible member connected at both of its ends to the free end of said Bourdon tube and coiled intermediate between its ends about said rotative member, an extensible element included 100 in one run of the flexible connection, and a collar having an opening, said collar being mounted upon the spindle and the flexible connection passing through an opening in the collar, one leg or run of said flexible member being wound above said collar and the other leg or run being wound below 105 said collar.

10. In a Bourdon tube gauge, a casing, a Bourdon tube and a spindle, a member rotatively mounted on said spindle carrying a dial hand or pointer, means to support one 110 end of the Bourdon tube, a flexible member connected at both of its ends to the free end of said Bourdon tube and having its intermediate portion coiled about said rotative member, an extensible element included in one run of the flexible connection and a collar having an opening, said collar being mounted upon the spindle and the flexible connection passing through the opening in the collar, one run or leg of said flexible connection being wound above said collar and the other leg or run being wound below 115 said collar, and means for clamping the flexible connection to the collar.

11. In a Bourdon tube gauge, a casing, a Bourdon tube arranged therein, said tube being anchored at one end, a dial hand or pointer, and means connected to the free 120 125 130 135 140

end of said tube for actuating said dial hand or pointer, in combination with a fulcrum abutment for said tube, said abutment interposed between said tube and casing, a carrier member for said abutment, said carrier member fitting and held against the inner wall of the casing, and adjustable in the direction of the length of the tube.

12. In a Bourdon tube gauge, a casing, a Bourdon tube arranged therein, said tube being anchored at one end, a dial hand or pointer, and means connected to the free end of said tube for actuating said dial hand

or pointer, in combination with a fulcrum abutment for said tube, said abutment interposed between said tube and casing, a carrier member for said abutment, said carrier member fitting and held against the inner wall of the casing, the wall of the casing having a portion thereof punched and pressed inwardly to form a loop, said carrier member extending through said loop.

In testimony whereof I have hereunto set my hand on this 14th day of April A. D., 1920.

ERNEST B. CROCKER.
